[57] CLAIM

The ornamental design for a control enhancing attachment for tweezers, as shown and described.

DESCRIPTION

FIG. 1 is an exploded top perspective view of a control enhancing handle attachment for tweezers showing my new design;

FIG. 2 is a left side elevational view of the assembled handle attachment, the side opposite being a mirror image of the side shown;

FIG. 3 is a bottom plan view of the lower component of the set, shown separately for clarity of illustration;

FIG. 4 is a left side elevational view thereof, the side opposite being a mirror image of the side shown;

FIG. 5 is a front end elevational view thereof;

FIG. 6 is a rear end elevational view thereof;

FIG. 7 is a bottom plan view thereof;

FIG. 8 is a top plan view of the upper component of the set;

FIG. 9 is a bottom plan view thereof;

FIG. 10 is a right side elevational view thereof, the side opposite being a mirror image of the side shown;

FIG. 11 is a front end elevational view thereof; and,

FIG. 12 is a rear end elevational view thereof.

The broken line showing of tweezers in FIG. 2 is for illustrative purposes only and forms no part of the claimed design.
